US00D939956S

(12) **United States Design Patent** (10) Patent No.: **US D939,956 S**
(45) Date of Patent: ** Jan. 4, 2022

(54) **CAN LID**

- (71) Applicant: **Silgan Containers LLC**, Woodland Hills, CA (US)
- (72) Inventors: **David Dunn**, Palmyra, WI (US); **Elizabeth A. Metzger**, Wauwatosa, WI (US); **John Schindewolf**, Rochelle, IL (US); **Alvin Widitora**, Los Angeles, CA (US); **Dave Wood**, Oconomowoc, WI (US); **Seth Moore**, Oconomowoc, WI (US); **Andrew Palumbo**, Conshohocken, PA (US)
- (73) Assignee: **Silgan Containers LLC**, Woodland Hills, CA (US)

(**) Term: **15 Years**

(21) Appl. No.: **29/761,485**

(22) Filed: **Dec. 9, 2020**

CLAIM

We claim the ornamental design for a can lid, as shown and described.

DESCRIPTION

FIG. 1 is a top view of an embodiment of the claimed design; FIG. 2 is a top perspective view of the embodiment of FIG. 1;

FIG. 3 is a top view of another embodiment of the claimed design;

FIG. 4 is a top perspective view of the embodiment of FIG. 3;

FIG. 5 is a top view of another embodiment of the claimed design;

FIG. 6 is a top perspective view of the embodiment of FIG. 5;

FIG. 7 is a top view of another embodiment of the claimed design; and,

(Continued)

FIG. 8 is a top perspective view of the embodiment of FIG. 8.

The ornamental design which is claimed is shown in solid lines in the drawings.

1 Claim, 8 Drawing Sheets
